UNITED STATES PATENT OFFICE.

MILUS M. HOUSE, OF KANSAS CITY, MISSOURI.

DENTAL TRITURATING APPLIANCE.

Application filed November 6, 1924. Serial No. 748,070.

The present invention relates to dental apparatus, and aims to devise a novel and more efficient form of triturating appliance for use with articulating or occluding operations involved in the making of artificial dentures or like work. The special object in view is to provide a device of this character which is adapted, by an improved mode of grinding or milling action, to correct or remove the inaccuracies present in imperfect occlusion.

In the proposed embodiment of the invention, I employ means for effecting a continuous unidirectional milling or grinding movement of one of the dentures with reference to the other, throughout the various positions of occlusion occupied by the dentures.

It is a further object of the invention to provide a construction which may be embodied in either a complete self-contained unit combined with the articulator or occluding frame, or as a separate attachment adapted for ready application to or removal from such appliances.

With these general objects in view, the invention will now be described by reference to the accompanying drawings illustrating one form of construction which I have devised for embodying the proposed improvements, after which those features deemed to be novel will be particularly set forth and claimed.

In the drawings—

Figure 1 is a side elevation illustrating an apparatus constructed in accordance with the present invention;

Figure 2 is a plan view of the same;

Figure 3 is a vertical sectional view, representing a section on the line III—III of Figure 2;

Figures 4 and 5 are detail sections on the lines IV—IV and V—V respectively of Figure 3; and

Figure 6 is a diagrammatic view to illustrate the rotative action of the eccentric and resultant movement of the plate carrying the upper denture.

Referring now to the drawings in detail, these illustrate the proposed improvements in relation to a form of articulator or occluding appliance in more or less common use. This appliance comprises a framework made up of a lower frame member 10 for the support of a horizontally adjustable bar 11 which carries the lower plastic mounting 12 for the lower denture 14; this bar 11 is provided with a front supporting leg 15 and

with a rear adjustable screw 16 journaled in the frame 10 adjacent to a stop or limiting screw 17 which determines the longitudinal position of the bar for central occlusion. 60 This bar is clamped in any desired position by means of a clamping screw 18.

The frame member 10 is formed with upwardly projecting arms 20 connected by aligned pivots 21 to the opposite extremities of a yoke member 22, the middle point of which is provided with an inclined pivot 24 for connection with the inclined rear end portion of the upper horizontal bar 25 designed to support the upper plastic mounting 26 for the upper denture 27. The rear end of this bar 25 is provided with a screw 28 which is pointed for engagement with a tapered recess 29 (see Figure 3) in the member 22, so as to either clamp the bar 25 in 70 central position or permit slight movement thereof in either lateral direction. At its other end, the bar 25 is provided with a bearing portion 30 and recess 31 for receiving the stem 32 and projection 33, respectively, of a 80 bracket 34 having a split sleeve portion 35 for mounting a screw post 36 adapted to be clamped by means of the external clamping collar 37 on the lower end of the sleeve 35. The lower end of the post 36 is adapted to be 85 received within a cup element 38 carried by the front end of the bar 11, this element 38 having downwardly converging walls designed for alining the post and the bar 35 in proper position for central occlusion. The 90 bracket 34 also carries a rotatable stop element 39 adapted to be turned into position for engagement with the head of the post 36 to limit its lowering movement in determining the parallel relation of the bars 11 and 95 25. A suitable clamping screw 40 is used to secure the stem 32 to the bearing 30.

The construction thus far described is for the most part common and well known, and the present improvement resides in the triturator device which I associate with the upper denture 27 and its mounting 26 for imparting thereto a continuous rotary movement of small amplitude. In the form of construction illustrated, I provide the plate 41 which carries the mounting 26 with a pin 42, and on the upper face of the bar 25 I secure a bearing block 43 by means of screws 44, and mount in said block an eccentric member 45 formed with an eccentrically located recess or socket 46 for receiving the upper end of the pin 42. An opening 47 is

provided in the bar 25, large enough to permit the play of the pin 42 in response to the action of the eccentric member 45. The latter is formed with an upwardly projecting shank 48 terminating in an attenuated extension 49 adapted to make connection with a flexible shaft coupling (not shown) such as that of a dental engine, or the eccentric may be rotated by means of a belt drive applied to a pulley 50 mounted on the shank 48 of the eccentric.

Various means may be employed for movably supporting the upper denture and its plate 41 from the bar 25, for the purpose of permitting the movements imparted thereto from the eccentric, the method illustrated comprising the use of a plate 52 adapted to rest on the top face of the bar 25 and connected by a rear screw 53 and two front screws 54 to the plate 41. The screw 53 is accommodated by an enlarged opening 55 in bar 25, while the screws 54 clear the opposite sides of the bar and carry suitable spacing blocks 56 (see Figure 4). In the middle portion of the plate 52 is cut an opening 57 amply large to clear the bearing block 43 (see Figure 5). By this means an easy floating support or bearing is provided for the upper denture and its mounting, adapted to facilitate complete freedom of movement thereof in response to the actuation of the eccentric.

The general method of using the appliance, including the operation of the improved triturative feature, will now be outlined. The frame parts are shown in Figures 1 and 3 as adjusted for the triturating operation in the position known as central occlusion, this position being determined by means of the various adjustments above referred to, including the seating of the lower end of the screw post 36 in the bottom of the cup 38, said screw being thereafter retracted or raised slightly, as shown, to transfer the weight of the pivoted parts to the lower denture 14. The usual grinding compound is applied to the dentures and the triturative action is then started by the operation of the eccentric through the medium of any suitable drive thereto. The method of mounting the upper denture 27 provides the same with a floating support adapting it for free movement in any direction about the combined axes of the pin 42 and eccentric member 45, the range of this movement being ample for covering the entire possible range of engagement or articulation of the dentures in all positions of occlusion. This range and the nature of the movement of the upper denture are outlined in the diagram in Figure 6, in which the arrows 60 indicate the direction of operative movements which various points A of the upper model or denture tend to execute in response to the action of the eccentric 45 rotating in the

direction indicated by the arrow 61. With the dentures in occluded relation, however, it is evident that the actual movement of the upper denture will be a modification of that illustrated, due to the irregularities in the teeth giving rise to a complex dragging effect upon the upper denture and imparting to it a correspondingly irregular movement. The range of pivotal movement of the denture-carrying plate 41 is also represented by dotted lines in Figure 6, this movement being of course limited, as by the engagement of the spacing blocks 56 with the adjacent sides of the bar 25 (Figure 4).

The object of this character of movement of the upper denture is to effect the milling or triturating action by the movement approaching as nearly as possible that of a mortar and pestle, by which action the desired grinding effect is best attained for removing or correcting the inaccuracies of imperfect occlusion. In the ordinary grinding operations on artificial dentures, beginning with the position of central occlusion, the grinding action is carried out with a reciprocating movement tending to produce a too great extent of flat surfaces in order to obtain the required play room for the teeth, and with a corresponding decrease in biting efficiency. In the present construction, the grinding movement is effected with a continuous approximately circular motion simulating the mortar and pestle action, which is that most truly adapted to the conditions existing between the high points or cusps (corresponding to pestles) of one set of teeth fitting in the sulci (like mortars) of the opposed teeth. As the grinding or milling action proceeds, this produces in the contacting portions of the teeth the curved facets more nearly resembling those produced in the natural use and wear of teeth than can be obtained by any other grinding method.

After grinding in central occlusion, the screw 28 is loosened and the operation is carried out for right and left lateral occlusion, and thereafter for protrusive and retrusive occlusion, for which purpose the screws 16 and 17 are adjusted to give the proper position to the lower denture.

The completion of the operation results in dentures having their occlusal surfaces of a substantially ideal character as regards functioning with a smooth, gliding movement, and having ample play room without any vertical movement of the lower jaw, besides which greater biting efficiency is attained by the elimination of flat surfaces as far as possible.

From the foregoing it will be apparent that I have devised a practical and highly efficient apparatus for carrying out the desired objects of the improvements, and while I have shown what I now regard as one approved form of embodiment thereof, I de-

sire to reserve the right to make all such changes or modifications as may fairly fall within the scope of the appended claims.

What I claim is:

- 5 1. An attachment for articulators or occluding frames, comprising a denture-holding element adapted for removable connection to the articulator or frame, said element being also adapted for universal floating movement in a single plane, and means for imparting to said element a continuous unidirectional movement of small amplitude.
- 10 2. A dental appliance comprising a pair of relatively adjustable denture-supporting members, a denture-holding element adapted for attachment to one of said members, and mounted for relative floating movement in a single plane, and means for imparting a continuous movement of small amplitude
- 15

to said element while permitting a pivotal or swinging movement of said element independent of said first movement.

3. A dental appliance comprising a pair of relatively adjustable denture-supporting members, a denture-holding element adapted for attachment to one of said members and mounted for relative floating movement in a single plane, means for actuating said element for imparting a continuous movement thereto of small amplitude while allowing a pivotal or swinging movement of the element independent of said first movement, and means for restricting the swinging movement of the element.

In witness whereof I hereunto affix my signature.

MILUS M. HOUSE.
